UNITED STATES PATENT OFFICE.

WARREN HENRY BRISTOL, OF BROOKLYN, NEW YORK.

BOY'S SIDE GARTER.

No. 822,180.

Specification of Letters Patent.

Patented May 29, 1906.

Application filed October 18, 1904. Serial No. 229,005.

To all whom it may concern:

Be it known that I, WARREN HENRY BRISTOL, a citizen of the United States, residing at Brooklyn, in the county of Kings and State of New York, have invented a new and useful Improvement in Boys' Side Garters, of which the following is a specification.

This invention relates to an improvement in stocking-supporting devices, and has for its object to provide a construction especially adapted for boys of the age who wear trousers which are supported by suspenders.

Heretofore great trouble has been experienced in finding some way of supporting the stockings of boys wearing short trousers and suspenders, and the supporters have usually been connected to the trousers or shirt; but this method does not hold the stockings up tightly, and consequently they droop and wrinkle around the shoe-tops or ankles, and to avoid this it has been necessary to draw the supporters so tight that the trousers or shirts are made to sag and the appearance of the dress greatly impaired.

It is therefore the purpose of my invention to overcome these objections and to provide a support which will not only be comfortable, but so adapted to the trousers that the sagging is avoided and the stockings firmly, securely, and comfortably held up.

Still a further object of my invention is to provide an arrangement which may be permanently connected, as it were, to the trousers and stockings and the necessity of entirely removing them each time the wearer makes his toilet avoided.

These objects I accomplish by providing a support which is firmly connected to the waistband of the trousers at the points where the suspenders are attached, which throws the entire weight upon the suspenders, and consequently the shoulders of the wearer, which provides a firm connection and permits of the stockings being tightly held up without causing the wearer the slightest discomfort.

With these briefly-stated objects in view my invention comprises certain details of construction and novelties of combination and arrangement of parts, as will be fully described in the following specification and pointed out in the claims, reference being had to the drawings, in which—

Figure 1 is a view showing the practical application of my invention. Fig. 2 is an enlarged perspective view of one of the sup-

porters. Fig. 3 is a detail side view of the clasp for connecting the supporters to the trousers, the trousers being shown in section. Fig. 4 is a detail front view of the same, the button being moved and a portion of the trousers being broken-away. Fig. 5 is a sectional elevation of the spring-hook and loop for uniting the two sections of the supporters. Fig. 6 is a detail perspective view showing the spring-hook and loop detached. Fig. 7 is a detail perspective view of one of the fasteners for connecting the supporter to the trousers, the fastener being shown closed; and Fig. 8 is a similar view showing the fastener open.

In carrying out my invention I employ two sections A and B for each supporter, and as the supporters are exactly alike the description of one is thought to be sufficient, and this will be followed throughout the specification. The sections are united by means of a spring-clasp C, which may be readily disengaged to separate the sections whenever desired and which when separated leaves one section attached to the trousers and the other section attached to the stocking.

The section A, which is connected to the trousers, comprises a non-elastic band D, folded to provide a double loop which operates through a metallic loop E, to which the spring-clasp C is connected. The free ends of the band D have my improved spring-fasteners F connected thereto, each fastener being constructed of a single strand of spring-wire bent to form the rectangular-shaped loop portion F', from which project the shank portions F'', whose outer ends are bent outwardly and downwardly to provide a hook F''' and the extreme ends bent to form semicircular portions F'', which when brought together form a complete circle that encircles the shank of the button when in position upon the trousers. The shanks and semicircular portions are firmly held together by means of a ring F', which slides upon the shanks F''. It will be readily understood that when the rings are pushed toward the outer ends of the shanks the latter will be held together and the fastener secured in place; but when the rings are pushed toward the loop end the shanks will open and the fasteners may then be readily disengaged.

By this construction of the fasteners it will be also seen that the outwardly-bent portions provide a hook which engages the top of the waistband of the trousers directly adjacent the buttons to which the suspenders are con-

nected, and consequently the strain placed upon the trousers by the weight of the stockings is at these points, and the suspenders are therefore employed to hold the stockings up.

5 Operating in connection with the non-elastic straps or bands D is the elastic strap G, forming the section B of the support, the lower end of the elastic G being provided with any suitable construction of a clasp H, 10 which is designed to engage the stocking, and the opposite end is connected to any suitable form of buckle I, by which the elastic may be adjusted to various lengths, as occasion may require. The loop formed in the 15 elastic operates through a non-circular metallic loop C', carried by the spring-clasp C.

From the foregoing it will readily appear that I provide an exceedingly simple and highly-efficient device that overcomes all objections now commonly experienced in supporters of this kind, and in operation the section A of each supporter is first connected to the trousers, so that one spring-fastener engages the trousers at the rear suspender-button, 20 and the other fastener engages the trousers at the side suspender-button, and when thus connected the section A is allowed to hang down inside the trousers. The section B, which forms the lower section, is then connected to the stocking by means of the clasp H, and the sections are then ready to be united, which is done by slipping the lower portion of the loop E into the spring-clasp C. This operation, as will be seen, is exceedingly 25 simple, and when the wearer is retiring or desires to remove his clothing the clasp C is disengaged from the loop and the upper section A is left attached to the trousers, while the lower section B is left attached to the stocking. 30 By this arrangement the parts are always ready and in position to be united when the wearer makes his toilet, and the very objectionable feature of the supporters being misplaced is always avoided.

40 It will of course be understood that by providing a sliding connection between the non-elastic band D and the elastic section B by means of the loop B' relative movement of the body of the wearer is freely allowed 45 without affecting the stockings, which are consequently always tightly held up, and, further, that by connecting the supporters to the points of the trousers, as hereinbefore described, all the strain incident to support-

ing the stockings is thrown entirely upon the 55 suspenders and of course upon the shoulders of the wearer, which greatly adds to his appearance and comfort.

Having thus fully described my invention, what I claim as new, and desire to secure by 60 Letters Patent, is—

1. A device of the kind described comprising upper and lower sections, said upper section comprising a double-loop band having a metallic loop slidably connected therewith, 65 and means connected to the ends of the band for securing the band to a waistband, the said lower section comprising an elastic strap having a spring-actuated clasp connected to the lower end of the said lower section and a 70 spring-clasp adapted for detachable connection to the metallic loop carried by the upper section.

2. A device of the kind described, comprising an upper section formed of a double-loop 75 band having spring-fasteners connected at their ends and a metallic loop slidably retained upon the band, and an elastic lower section having means carried by one end to adapt the section to be secured to a stocking 80 and a spring-actuated clasp adapted for connection with the said metallic loop.

3. A device of the kind described comprising the upper and lower sections, spring-fasteners carried by the upper section, said fasteners comprising the loop portions, having shanks projecting therefrom, the outer ends of which terminate in hooks and the extreme ends bent to form semicircular portions, the rings operating upon the shanks, the clasp 90 carried by the lower section and the spring-clasp carried by the lower section and adapted for engagement with the upper section.

4. A device of the kind described, comprising an upper section composed of a non-elastic 95 band arranged to provide a double loop and having spring-fasteners connected to the ends thereof adapted to secure same to a waistband, a metallic loop slidably held upon each section of the band-loops, the lower section comprising an elastic band having a spring-clasp for engagement with the said metallic loop and a spring-clasp connected to its lower end for attachment to a stocking. 100
